UNITED STATES PATENT OFFICE.

JAMES M. BRESEE, OF MATTOON, ILLINOIS.

ROAD-MACHINE.

1,201,249.

Specification of Letters Patent. Patented Oct. 17, 1916.

Application filed November 20, 1913. Serial No. 802,130.

To all whom it may concern:

Be it known that I, JAMES M. BRESEE, a citizen of the United States, residing at Mattoon, in the county of Coles and State of Illinois, have invented certain new and useful Improvements in Road-Machines, of which the following is a specification.

This invention relates to improvements in road machines, and has for its principal object to provide such a machine having improved means for raising, lowering and adjusting the position of the scraper bars and also to provide improved means for holding the scraper bars in adjusted position.

Another object of my invention is to provide an improved construction embodying arms extending from the body of the machine to the scraper bars adapted to maintain them in extended position, together with a track support for the ends of said arms and means to lock them in adjusted position.

Another object of my invention is to provide a machine of the class described, in which the means for controlling the scraper bars are all located in convenient position for handling by one operator without necessity for his moving from a comparatively limited space.

These and other objects are set forth in the following specification and shown in the accompanying drawings, in which:

Figure 1 is a plan view of my machine; Fig. 2 is a front elevation of the same; Fig. 3 is a detail section taken along the line 3—3 of Fig. 4; Fig. 4 is a side elevation of my machine; Fig. 5 is a detail of the locking mechanism; Fig. 6 is a detail of the arm and scraper bar construction showing the scraper bars in section; Fig. 7 is a side elevation of the same; Fig. 8 is a detail section along the line 8 of Fig. 4; Fig. 9 is a detail showing a locking member in non-locking position.

Like numerals refer to like elements throughout the drawings, in which—

1 and 2 designate scraper bars, one on each side of the machine, said bars being capable of being spread apart a considerable distance at their forward ends and converging in such position at their rear ends when operating on wide roads. The amount of extension or spreading of the scraper bars may be adjusted according to the varying

widths of the roads on which my machine is used, as desired.

To maintain the bars in spread relation, I provide links or arms 3 and 4 which bend over at one extremity and are pivotally attached to a respective scraper bar 5 and 6, as shown in Fig. 2, for example. These arms 3 and 4 extend upwardly from the scraper bars over the body of the machine and are pivotally secured together at their inner extremities by a pin 7, projecting through eyes or holes in the flattened ends 3^a and 4^a respectively, of arms 3 and 4. Upwardly of the portions 3^a, 4^a, the pin 7 is reduced in diameter to form a shoulder 7^a, and terminating in threaded portion 7^b for engagement by nut 23. Lying upon the upper arm 4, upon the flattened portion 4^a thereof is a plate 17, suitably apertured to permit insertion therethrough of the reduced portion of pin 7 and contacting with 75 and supported on shoulder 7^a thereof. Located upon the plate 17 is the angle 21 having the flange 21^a secured to the plate 17 by nut 23. It will be apparent that this nut will serve to securely clamp plate 17 in 80 position against the shoulder 7^a of pin 7. Longitudinally arranged channel beams 9 and 10, having their channels inwardly turned and spaced apart, as shown in Fig. 8, for example, are carried by the machine 85 and are secured to and suitably braced by means of brace members 11, 12, extending from the main longitudinal beams A, B, of the body of the machine. The channel beams 9, 10, are provided with the inwardly turned upper flanges 9^a, 10^a, respectively, upon which lies the flattened portion 3^a of the lower arm 3 of arms 3 and 4. The flanges 9^a, 10^a are spaced apart sufficiently to permit the sliding therebetween of the 95 pin 7. A plate 8 is carried upon the head 7^c of the pin 7 in sliding contact with the under surfaces of flanges 9^a, 10^a, being formed on its upper surface to fit the contour of the lower surfaces of such flanges. It will 100 be apparent that this construction is adapted to permit sliding of the arms relative to the track members 9, 10, without permitting their displacement therefrom, the pin 7 and nut 23 serving to prevent clamping or binding of the plates and arms to the track members. Pins 18, 19 located on either side of the pin 7, extend between the plates 8

and 17 and are provided with the enlarged portions located between the plates and forming shoulders to limit the drawing together of the said plates to cause clamping 5 or binding of the sliding members. This is clearly shown in Fig. 5 of the drawings, for example, this construction providing a compact and simple form of track and slide.

Uprights 29 are secured to the channel 10 bars 9, 10 by rivets or the like through their flanges 29^a, and extend upwardly of the said track members, as clearly shown in Fig. 8, adjacent each end of the track. Cross bars 27 extend across between the tops of the 15 uprights 29. A locking bar 30 extends between the cross bars 27, and is provided with studs or lugs at each end, indicated by numerals 30^a, these studs being pivotally mounted in suitable apertures in the cross bar 27. This 20 locking bar 30 is preferably T-shaped and provided with the main flange 30^b and cross flange 30^c. The upright flange 30^b is notched as indicated by numerals 24, these notches being arranged for engagement with the 25 right flange of locking member 21, as clearly shown in Fig. 5.

An operating lever 31 is secured to and 30 extends upwardly from the cross flange 30^c of locking bar 30 and is located preferably adjacent one end thereof. It will be apparent that this lever may be moved to partially rotate the locking member 30 so as to cause disengagement of the notches 24 with the locking member 21, so that the ends of the 35 arms 3 and 4 may slide relative to the track, as desired. In order to maintain the locking bar in locking or non-locking position, I may thread one end of the stud 30^a and provide a nut 30' thereon, a washer 30" being located between the nut and the cross bar 27 so that tightening of the nut 30' will press the washer 30" against the said cross bar increasing the frictional contact therewith so that while rotation of the locking 40 bar 30 will be permitted, it will be retained in an adjusted position.

The arms 3 and 4, as stated above, are bent over the scraper bars 1 and 2 and bent back thereto as indicated by numerals 3^b, 4^b, respectively, being pivoted at their extremities to the scraper bars, as clearly shown in Fig. 6, for example, a pin 84 being inserted through an aperture in the extremity of the respective arm and serving to secure the 55 same between the parallel flanges of angle bars 85, 86, each of which has a flange secured to a channel bar 87, which in turn is secured by angles 88 to the curved scraper blade 89. A strap 90 is secured around the 60 bent portion of the bars 3 and 4, as shown in Figs. 6 and 7, and serves to strengthen and reinforce the same.

Carried by the body members A, B, adjacent their rearward portion, are the supporting braces C, D, providing an upwardly

extending support for the pulley 71, over which extends an operating cable or chain 66, to and partially around a second pulley 72, which is rotatably connected to the chain 72^a, secured at its spaced apart extremities to a cross bar 73, to which in turn are pivotally secured, adjacent their rear extremities, the scraper bars 1 and 2. One end of this cable or chain is secured to the supporting structure C, D, and the other end extends longitudinally of the machine to a drum mounted upon shaft 68, extending upwardly of the body and provided with the operating handle wheel 68^a, rotation of which will raise or lower the rear portion of the scraper bars. This being a well-known construction and forming no part of my present invention, it will not be necessary to more fully describe the same. Chains 77, 78 extend from the cross bar 73 to the body of the machine, and are secured thereto. These chains are relatively crossed, and thereby serve to resist lateral swaying or movement of the scraper bars 1 and 2.

Adjacent the forward portion of the body 90 of the machine are located raising and lowering members 34, 35, shown as U-shaped, being in effect of yoke-like construction. These yokes are pivotally attached at their free ends to the body members A, B, respectively, and are provided with pulley blocks 42, 43, respectively, pivotally mounted adjacent the upper portion of the yoke. Operating cables or chains extend around the respective pulleys in these blocks to and around pulleys 54, 55, respectively, secured to the bars 1 and 2, and from thence extend upwardly to and around other pulleys in the blocks 42, 43. They then extend downwardly to and are secured to the eye-bolts 56, 57 carried by the cross beam 81. At their other ends these cables or chains are wound around drums 58, 59, pivotally supported between uprights 58^a, 59^a, which, in turn, extend upwardly from and are secured to the extremities of cross beam 81. This cross beam is supported upwardly of the body of the machine by uprights 82, which are themselves secured to the longitudinal frame members A, B, as shown in Fig. 2. Rods 58^b, 59^b extend between the pairs of uprights 58^a, 59^a, respectively, upwardly of the drums 58, 59. Hand wheels 60, 61, are mounted upon the shafts of the drums 58, 59, respectively, and pawl and ratchets or similar mechanisms 62, 63, are provided for locking the drums 58 and 59 in desired position. Shackles or eye bolts 34^a, 35^a are provided in the upper portions of the yokes 34, 35, and cables or chains extend therefrom to and around a drum 46, carried between uprights 46^a extending upwardly from the cross beam 81. A hand wheel 47 is operatively secured to this drum 46 and a suitable pawl or ratchet or similar mecha- 100 105 110 115 120 125 130

nism is provided therefor. Rotation of the hand wheel 47 will operate to simultaneously raise or lower the two yokes 34, 35, as desired, and they may be held in adjusted position by the pawl and ratchet 46^b.

It will be apparent that in the operation of my improved device, assuming the same is in operative position relative to the road upon which it is to be used, the pawl and ratchet 46^b may be thrown out of engagement to release the drum 46 and thereby lower the yokes 34, 35 to the desired position. At the same time the operating lever 31 may be moved to the position indicated 15 in Fig. 9, thereby permitting free sliding of the ends of the arms 3 and 4. The ratchet 69 may then be released from engagement with the pawl 70, permitting the drum 67 to unwind and allowing the rear 20 portion of the scraper bars to be lowered to the road. Similarly drums 58 and 59 may be released to permit the front portion of scraper bars to contact with the road and to move to operative position. The contact between the road and the scraper bars will 25 operate to spread the latter to the greatest possible width permitted by the adjustments and by the amount of cable or chains 52, 53, unwound, thereby permitting adjustment 30 for variation in the width of the road. A certain amount of lateral adjustment may be also made by means of raising or lowering the yokes 34, 35. It is to be noted that when the bars have spread to the position 35 desired, the lever 31 may be raised to an upright position, thereby causing the corresponding of the notches 24 on bar 30 to engage with the member 21 to thereby prevent further lateral movement of the scraper bars. 40 This insures rigidity of the latter with respect to the road when in operation thereon. To move the bars to inoperative position, it is only necessary to reverse the above movements, it being noted that sufficient play and 45 flexibility is present in and between the link arms to permit raising and lowering of the scraper bars.

It will be apparent that I have provided a simple and efficient form of road machine, 50 capable of ready and quick adjustment to desired position. It will also be apparent that my device is susceptible of many changes and modifications and I do not wish to be restricted to the form shown or described, beyond the scope of the appended claims.

I claim—

1. In a machine of the class described, a body, a scraper at each side of said body, said scrapers being pivotally connected to said body adjacent their rear extremities, a supporting arm pivotally attached to said body at each side thereof, said arms each being connected to a scraper, means to raise and lower said arms simultaneously in order

to raise and lower said scrapers, and means to raise and lower said scrapers with respect to their respective supporting arms independently of each other.

2. In a machine of the class described, a body, scraper bars, a pair of yoke shaped supporting arms pivotally attached to said body and carrying pulleys, a pair of winding drums mounted on said body, a cable member carried by each of said drums and extending around each of said pulleys to the respective of said scraper bars whereby said drums may be rotated to raise or lower said scraper bars, a third winding drum, cables mounted on said last named winding drum 75 and extending to and secured to said supporting arms whereby rotation of said last named drum will operate to raise or lower said supporting arms.

3. In a machine of the class described, a body, scraper bars, a pair of yoke shaped supporting arms pivotally attached to said body and carrying pulleys, a pair of winding drums mounted on said body, a cable member carried by each of said drums and 85 extending around each of said pulleys to the respective of said scraper bars whereby said drums may be rotated to raise or lower said scraper bars, a third winding drum, cables mounted on said last named winding 90 drum and extending to and secured to said supporting arms whereby rotation of said last named drum will operate to raise or lower said supporting arms, all of said drums being located adjacent a common 95 point.

4. In a machine of the class described, a body, scraper bars, means carried by said body to raise or lower said scraper bars and to positively move said scraper bars inwardly or outwardly with respect to said body, and means comprising parts movable longitudinally of said body to fix said scraper bars in the desired position outwardly of said body.

5. In a machine of the class described, scraper bars, a body, means carried by said body to raise or lower said bars, a track mounted on said body, link arms extending from adjacent said track to and attached to 110 said scraper bars, said link arms being pivotally attached, a flange member attached to said arms, and means coacting with said flange member to lock said link arms in adjusted position, said means comprising a 115 bar notched to engage said flange member and secure the same in adjusted position with respect to said track.

6. In a machine of the class described, scraper bars, a body, means carried by said body to raise or lower said bars, a track mounted on said body, link arms extending from adjacent said track to and attached to 125 said scraper bars, said link arms being pivotally attached, a flange member attached 130

to said arms, and means coacting with said flange member to lock said link arms in adjusted position, said means comprising a bar notched to engage said flange member and secure the same in adjusted position with respect to said track, said notched bar being movable to engage or disengage said flange member, as desired.

7. In a machine of the class described, a body, scraper bars, a track mounted on said body and extending longitudinally thereof, link arms extending from adjacent said track to and pivotally attached to said scraper bars, a locking member having said links pivoted thereto and arranged to slide on said track, and a notched T-bar mounted substantially parallel to said track and arranged to engage said locking member, said notched bar being balanced and adjusted to be retained in either operative or inoperative position.

8. In a machine of the class described, scraper bars, a body, a track mounted on and secured to said body and comprising a pair of flanged beams each having a flange turned toward the other, and link-arms having their ends pivotally attached together and to a pair of plates mounted one above and one below said inturned flanges to slide relative thereto.

9. In a machine of the class described, scraper bars, a body, a track mounted on and secured to said body and comprising a pair of flanged beams each having a flange turned toward the other, link-arms having their ends pivotally attached together and to a pair of plates mounted one above and one below said inturned flanges to slide relative thereto, a member secured to said plates and having a flange portion, and a locking bar arranged to engage said flange portion when desired to lock said link arms against sliding relative to said track.

10. In a machine of the class described, a body, scraper bars, a track mounted on said body and extending longitudinally thereof, link arms pivotally attached to said scraper bars and extending to said track, a locking member having said links pivoted thereto and arranged to slide on said track, and a notched bar mounted substantially parallel to said track, said notched bar being arranged to permit engagement thereof with said locking member when desired.

11. In a road machine, a body, a scraper bar, supporting means pivotally attached to said machine, raising means operatively connected with said supporting means for lowering said scraper bar away from or raising it toward the point of said connection on said supporting means, and independent means to raise or lower said supporting means to raise or lower said scraper bar.

12. In a road machine, a body, a scraper bar, a supporting member pivotally attached

to said body to swing outwardly and downwardly therefrom, means coöperating with said supporting member to raise or lower said scraper bar, a link member extending to said bar, said link member being pivotally secured thereto, and means to lock said link member in adjusted position, whereby said scraper bar will be held against movement inwardly or outwardly.

13. In a machine of the class described, a body, scraper bars, means carried by said body to raise or lower said scraper bars and to positively move said scraper bars inwardly or outwardly with respect to said body, and means comprising link arms extending to each scraper bar and inter-connected above said body for fixing said scraper bars in the desired position outwardly of said body.

14. In a machine of the class described, a body, scraper bars, supporting means movable transversely of said body for moving said scraper bars inwardly and outwardly with respect to said body, extensible means for securing said scraper bars to said supporting means, and means comprising parts movable longitudinally of said body for securing said scraper bars in the desired position outwardly of said body.

15. In a road machine, a body, a scraper bar at one side of said body having its rear portion pivotally connected to and adapted to be raised or lowered with respect to said body, a supporting member attached to the forward portion of said body and adapted to be raised or lowered with respect thereto, adjustable means to raise and lower said supporting member, and extensible means for securing said scraper bar to said supporting member.

16. In a road machine, a body, scrapers carried by said body at each side thereof, means to move said scrapers inwardly or outwardly with respect to said body, and independent means comprising elements pivotally connected to said scrapers and adjustable with respect to said body for fixing said scrapers in the desired position outwardly of said body, said elements of said last named means being automatically movable to the desired position with respect to said body by the operation of said first named means.

17. In a machine of the class described, a body, a scraper bar having its rear portion pivotally connected to said body and adapted to be raised or lowered with respect thereto, a U-shaped supporting member having its ends pivoted on the side of said body adjacent the forward portion thereof whereby said supporting member will swing outwardly in a vertical plane transversely to the longitudinal axis of said body, extensible means operatively connected with the outward portion of said supporting

member and extending to said scraper bar to raise or lower the forward portion of said scraper bar with respect to said supporting member, and means to adjust said 5 supporting member to the desired angular position with respect to said body.

18. In a machine of the class described, a body, a U-shaped supporting member having the ends of the arms thereof pivoted on 10 the side of the said body adjacent the forward portion thereof, whereby said supporting member may swing outwardly and downwardly with respect to said body transversely to the longitudinal axis thereof, a 15 scraper bar connected adjacent its forward end to the outer portion of said supporting member and having its rear portion pivotally connected to said body, and means to raise and lower said supporting member 20 about its pivotal connections.

19. In a machine of the class described, a body, scraper bars, supporting means movable transversely of said body for moving said scraper bars inwardly and outwardly 25 with respect to said body, and means comprising parts movable longitudinally of said body for securing said scraper bars in the desired position outwardly of said body.

20. In a machine of the class described, a 30 body, a supporting member having its inner

and lower end pivoted on the side of said body adjacent the forward portion thereof, whereby said supporting member may swing outwardly and downwardly with respect to said body transversely to the longitudinal 35 axis thereof, a scraper bar connected adjacent its forward end to the outer portion of said supporting member and having its rear portion pivotally connected to said body, and means to raise and lower said supporting member about its pivotal connections. 40

21. In a machine of the class described, a body, a scraper at each side of said body, said scrapers being interconnected adjacent their rear extremities, a pair of supporting 45 arms each pivotally attached to one side of said body adjacent the forward portion thereof, said arms being arranged to swing outwardly and downwardly from said body, each of said arms being connected at its 50 outer extremity to a scraper, and means to raise and lower said arms simultaneously by a single operating means in order to raise and lower said scrapers.

In testimony whereof, I have subscribed 55 my name.

JAMES M. BRESEE.
